UNITED STATES PATENT OFFICE.

DANIEL FREDERICK DICKERMAN AND MIKE MOORE, OF NOCONA, TEXAS.

STIRRUP.

SPECIFICATION forming part of Letters Patent No. 627,328, dated June 20, 1899.

Application filed October 7, 1898. Serial No. 692,915. (No model.)

To all whom it may concern:

Be it known that we, DANIEL FREDERICK DICKERMAN and MIKE MOORE, citizens of the United States, residing at Nocona, in the county of Montague, State of Texas, have invented certain new and useful Improvements in Stirrups, of which the following is a description, reference being had to the accompanying drawings and to the letters of reference marked thereon.

Our invention relates to improvements in stirrups, our object being primarily to produce a stirrup in which the strap-bar or equivalent member is held away from the instep of the rider and prevented from jamming upon the same. Heretofore it has been sought to remedy this difficulty by constructing a stirrup having the tread-plate and the strap-bar offset with respect to each other; but in practice this attempt has been unsuccessful.

To the end above indicated and also to improve generally upon devices of the nature mentioned our invention consists in the various matters hereinafter described and claimed.

In the accompanying drawings, Figure 1 is a perspective view of a stirrup constructed in accordance with the present invention, a portion of the stirrup-strap being attached. Fig. 2 is a central sectional elevation of the same; and Fig. 3 is a front elevation, the strap being removed.

Referring now more particularly to the drawings, *a* represents the tread-plate of a stirrup, and *b* the stirrup sides, said sides each extending upwardly from the tread for a convenient distance in substantially the usual manner and then having forward and upward extensions *b'*, the tread and side pieces forming a substantially U-shaped article. Secured to these extensions and extending between the same is the strap bar *c*, the construction of the sides previously indicated being such that the strap-bar and the tread-plate are offset with relation to each, the strap-bar being here about in line with the forward edge of the tread. It will now be apparent that the strap *e* being applied to the strap-bar in the usual manner and the rider's foot inserted in the stirrup, with the heel in contact with the rear edge of the

tread, the instep is thrown in rear of the strap-bar, and thus when the tread-surface is substantially at right angles to the strap the strap-bar is held away from the instep. As soon, however, as pressure is removed from the rear edge of the tread the stirrup, were it composed of only the parts heretofore enumerated, would swing about the strap-bar as an axis until the strap-bar is above the body portion of the tread, or, in other words, until the parts assume substantially the relation of such parts in the usual form of stirrup. To overcome this difficulty and to hold the stirrup in proper position at all times, we provide means for preventing the downward and forward falling of the tread upon the strap-bar as a pivot, and, as here shown, this comprises a stop-bar *d*, secured to the side extensions *b'* and extending between the same, this stop lying slightly in advance of and above the strap-bar, whereby the strap has its forward member in rear of the stop and in front of the strap-bar, the strap being looped about the said strap-bar in the usual manner. It will now be seen that the tread cannot possibly fall, and the strap-bar is therefore at all times held away from the instep, while in addition to this the tread is at all times held in proper position, so that should the rider "lose" his stirrup the foot can be reinserted at once. Furthermore, the parts being arranged, as indicated, with the stop in advance of the strap, it is impossible for the stirrup end above the strap-bar to work into the loop of the strap and throw the stirrup out of proper position. The stop-bar also forms an additional brace for the stirrup sides.

The present stirrup comprises but a minimum number of parts which are light and are cheaply made and assembled; but by reason of their arrangement they combine to effectually prevent the unpleasant jamming of the strap-bar upon the instep, and the stirrup thus formed is strong and comfortable, with the parts always in proper position.

Having thus described our invention, what we claim as new, and desire to secure by Letters Patent, is—

A stirrup comprising a tread, side pieces extending upwardly from said tread and having their upper portions extending forwardly

as described, the tread and side pieces forming a substantially U-shaped article, a strap-bar extending between the forwardly-extending upper portions of the side pieces whereby said bar is in advance of the rear of the tread, and a stop-bar between the said forwardly-extending portions of the side pieces and above and slightly in advance of the strap-bar, whereby when a strap is applied to the strap-bar it rests against the rear of the stop-

bar and thus prevents falling of the tread; substantially as described.

In testimony whereof we affix our signatures in presence of two witnesses.

DANIEL FREDERICK DICKERMAN.
MIKE MOORE.
